HOIST DRUM MOUNTING

Edmond M. Wagner, San Marino, and James Moon, Altadena, Calif., assignors to Western Oil Tool & Engineering Co. Inc., Glendale, Calif., a corporation of California

Application March 12, 1946, Serial No. 653,874

9 Claims. (Cl. 254—187)

1

This invention relates to a drum mounting, and particularly to a hoist or winch drum mounting employing live shaft.

It is an object of the invention to construct a hoist drum mounted on a stub shaft or other live shafts.

It is a further object of the invention to apply the driving force directly to the drum with the stub shaft acting primarily as an axle.

It is a further object of the invention to provide for selectively connecting and disconnecting the drum from the driving means so that the drum may be driven by the driving means or may operate as a free-wheeling drum.

It is a further object of the invention to construct such a drum device in which a water-cooled air or hydraulic operated clutch is employed as the means for connecting the drum to the driving means, and particularly one in which the air or hydraulic pressure is applied at the axis of the drum axle.

It is a further object of the invention to construct a drum shaft mounting in which independent bearing systems are used, for example, two independent bearing systems, one of which, located at the driven end of the drum, takes substantially the entire rotational load when the drum is driven, with the second system, also located at the driven end of the drum, taking substantially only the static loads when the drum is driven.

It is a further object of the invention to construct the drum in a simple and light-weight manner with simple and independently replaceable end shaft constructions and mounting, and which may be driven at different speeds by "hi-low" drives at the ends of the drum.

These and other objects will be apparent from the further description of a preferred embodiment of the invention, taken together with the drawings, in which

Fig. 1 is a plan assembly view of the drum of the invention; and

Fig. 2 is a vertical section of one end of the drum; and

Fig. 3 is a vertical section through the rotor seal.

The drum 1 which has internal longitudinal strengthening ribs 2 carries a groove jacket or spool 3. The drum 1 is bolted to a flange 4 and to a shaft, bearing and clutch sprocket assembly of like construction at the ends A and B of the drum, axially mounted on the shaft. Suitable end supports, i. e., pillow blocks, are provided which may be mounted on a suitable foundation

2

or structure designed to receive the drum. This obvious feature is not shown. Ends A and B are constructed exactly alike except that the end B carries a sprocket and a clutch of smaller diameter than the end A. When mounted for operation the sprocket 10 of ends A and B are each always connected to the source of motive power and in rotation loads may be instantaneously transferred from end A to end B to drive the drum selectively at two different speeds by merely throwing a valve to transfer the air pressure from one clutch to the other.

Since both ends A and B are similarly constructed only the end A will be described.

15 The drum 1 is bolted to the drum flange 4 which is formed with a hub 5. Positioned in hub 5 is the stub shaft 6 held in place, by the draw bolt 7, against the end of the hub 5 by means of a shoulder 6'. Bearings 8 and 9 are mounted 20 longitudinally spaced on the stub shaft 6. While ball bearings are shown, other types of roller bearings may be employed.

25 The sprocket disc 10 upon which sprocket 10' is bolted is formed with the hub 11 which is bolted to the stirrup 12 by bolts 13. The bearings 8 and 9 are held in place by the hub 11 and stirrup 12 against shoulders suitably formed in the shaft 6. The hub 11 is spaced from the stub shaft 6 so that the shaft is not in driving or frictional contact at the opposing surfaces of 11 and 12 under any condition of loading.

30 Mounted exteriorly of the stirrup 12 and retained by shoulders formed in the stirrup 12 and on the sprocket disc 10 is a thrust roller bearing 15. The pillow block 16 is mounted on the bearing 15. The bearing 15 is restrained by ring 18' on one end (A) and not restrained by a ring 18' on the other end. This permits movement due to expansion thereof, imposing no thrust load on

35 15 as a result of such expansion. Lubrication 40 passageways 15' are provided connecting the bearings 15, 8 and 9 so that one shot lubrication, through a connection not shown, to the bearing 15 will also lubricate the bearings 8 and 9. Rotary seals 17 retained by ring 18 and other like 45 40 rotary seals 17 are positioned between the pillow block and the sprocket disc 10, end cap 14, and also between the stirrup 12 and retaining ring 18 mounted on the pillow block 16. These, in co-operation with the closure 19 mounted at the 50 end of the drum shaft and bearing assembly, act to contain the lubricant.

A bore 21 is formed in the end of the closure 19 and connects with a bore 22 formed in an 55 external rib 20 on the closure 19. The bore 22

connects with a bore 23 in the stirrup 12 and with a bore 24 in the hub 11. To the bore 24 is connected the air hose line 25 of the air-operated clutch to be described below.

Air is admitted under pressure to the bore system by a line 38 passing through the pillow block and connected to the rotary air seal 37 mounted in the bore 21.

The clutch is constructed to be air-operated as follows. A housing 26, co-axial with the shaft, is bolted to the sprocket disc 10. The housing holds an inflatable pneumatic tube 27 on which is positioned a clutch pressure plate 28. A plurality of leaf springs 29 are positioned in uniform spacing around the periphery of the plate 28 and held in place in holes formed in the sides of the housing 26. Upon the springs 29 is mounted a clutch plate 30 having a suitable surface for frictional engagement with the clutch ring 31, which, together with the brake flange 32, is mounted on the drum flange 4. The clutch faces are therefore parallel to and co-axial with the shaft 6. The brake drum flange 32 is grooved at 33 and spaced from the clutch ring 31, so that a circumferential opening 34 is provided into which may be placed a stationary water line 35.

On the exterior surface of the brake flange 32 is mounted a conventional brake block 36 which may be operated by hand or power means in any conventional manner to engage the brake flange for braking purposes.

Upon application of air pressure through 38 the tube 27 expands, thus forcing the split plate 30 to expand and forcing the spring 29 to expand the split clutch plate 30 against the inner face of the plate 32.

The sprocket 10' of the end A is connected to the drum via the clutch and thus to the hub 5 and the shaft 6. Thus shaft 6 and the disc 10 are rotating at the same R. P. M. and the bearings 8 and 9 are stationary. The rotational loads are transferred from the sprocket disc 10 and through the hub 11, stirrup 12, to the pillow block via the bearing 15. The static loads on the drum are transferred to the pillow block 16 via bearings 8, shaft 6, and through the bearing 9 to the stirrup 12, and via the bearing 15 to the pillow block 16. The thrust load on the drum is transferred from the draw-bolt through 9, against which it abuts, to 15.

Referring to the condition in end B, the clutch is disengaged so that the end B is in free-wheeling condition, i. e., the sprocket disc 10 of end B is disengaged from the rotating drum. The stub shaft 6 of end B rotates at the R. P. M. of the drum. Since the sprocket at end B is of smaller diameter and rotates at a higher R. P. M. than that of end A, the sprocket 10, the hub 11, and the stirrup 12 of end B will rotate at a higher R. P. M. than the shaft 6 of end B. Of course, the sprockets may be of the same diameter if driven from different power sources which will drive the sprockets each at the desired speed. The end to be obtained is to drive the end sprockets at different speeds. The bearings 8 and 9 of end B thus rotate and are not stationary as in the case of the same bearings in end A when the end A is driven.

The condition described above also exists in similar manner when the power is applied to end B by clutching at end B and declutching at end A. This can be done almost instantaneously by a valve (not shown) in line 38.

When the drum is free-wheeling, with both ends A and B declutched, as, for example, when

a line is being unreeled from the drum, as when a weight is being lowered, the condition described for the free-wheeling end obtains at both ends A and B. The drum speed is controlled by the brake 36. The water mist enters the grooves 33 and is vaporized by the frictional heat to thus cool the brake and clutch ring during clutching to overcome frictional heat developed during slippage.

The drum during free-wheeling at both ends A and B thus rotates at a different speed and in a direction reverse to the direction of rotation of the sprockets at both ends A and B. The bearings 8 and 9 rotate and take the rotational loads which are, of course, lighter than the rotational loads exerted when such weight is lifted by application of power to end A or end B with the drum suitably clutch-connected to the driving means.

Ball and roller bearings will carry much greater static loads when they are stationary than when they are rotating. We may thus employ smaller bearings 8 and 9 and place them closer together than where the static loads of the loaded end are to be transferred through rotating bearings. This is also aided by placing the bearing 15 between the bearings 8 and 9 and making the bearing 15 of a greater diameter than 8 and 9. This places bearing 15 exteriorly of the stirrup 12. This divides the radial loads between 8 and 9 and transfers the loads to 15. The bearings can thus be made of a size adequate to take the static and rotational and shock loads without requiring undue increase of the length of the shaft and hub assembly. The bearing 15 can be made sufficiently large to take and transmit the entire thrust load, static load, and rotational load without requiring the extension of the length of the shaft other than is required for positioning of the static load bearings. This is accomplished for the chain loaded end of the drum by employing two bearing systems, one a stationary bearing system to take and transmit the static portion of the load, and another to carry the rotational load.

In many uses, as, for instance, in drums mounted on trucks and tractors, the space between the support for the pillow block and the end of the drum shaft is limited and it is necessary to have as compact an arrangement as possible.

This spacing and arrangement of the bearings also permit for the axial application of the air pressure for actuation of the clutch. The closure member 19 is mounted so as to rotate with the hub 11. The stirrup and sprocket hub arrangement provide for air passageways to permit of the application of the air pressure to the tube 25. By positioning the rotor seal 37 at the axis of 7, I can provide for the sealing off of the tube 37a which is threaded to and locked into the bore 21 and rotates in a seal in 37.

The rotor seal 37 is shown in section in Fig. 3. The tube 37a rotates inside the housing of 37. The shoulder 39 is spaced from the shoulder 40. The ball race 41 is slidably mounted in 37 against a thrust ring 42. A like ball race 43 is slidably mounted in 37 against a thrust ring 44 and cover 45. The tube 37 has bores 46 for admission of air and carries by a shrink fit the ball race 48 retained against a ring 47 mounted in 37a. The ball race 49 is carried by a shrink fit on tube 37a against the shoulder 50. Leather washer 51 or similar packing is mounted in tube 37a by means of springs 52 and operate in housings 53. The packed off area in 37 is small and the peripheral

5

speed of the packed off surface of 37a is relatively low, and therefore it can hold the necessary high air pressures notwithstanding the relatively high speed at which the drum rotates. The special arrangement of the hub 11 to be mounted on the two bearing systems 15 and 8 and 9 makes possible the establishment of an air passageway between 37 and 25.

By the use of the bearing systems described above we are enabled to apply the air pressure for actuation of the air clutch axially of the drum shaft and provide communication between this axially applied air pressure and the clutch.

This construction also avoids the necessity for employing a shaft passing entirely through the drum. In such forms, both when the power is applied to the shaft and when applied to the drum, the portion of the shaft positioned inside the drum adds weight and little strength to the drum. We have thus cheapened and simplified the construction in this respect.

Variations of the above design will be apparent to those skilled in the art. For example, the sprocket may be replaced by a gear or pulley and the air clutch replaced by an oil-operated or mechanically operated clutch.

While we have described a particular embodiment of the invention for the purpose of illustration, it should be understood that various modifications and adaptations thereof may be made within the spirit of the invention as set forth in the appended claims.

We claim:

1. A drum assembly comprising a drum, a shaft, said drum being mounted on said shaft, a sprocket, a hub for said sprocket, axially mounted on said shaft, a clutch for connecting the drum and said shaft to said sprocket, an end support for said shaft, a bearing assembly between said shaft and said support, said bearing assembly comprising bearings between said sprocket hub and said support for transferring rotational loads from said sprocket to said support, other bearing positioned between said sprocket and said shaft, said bearings being positioned in series load-transfer relation with said shaft, said load-transfer relation including in sequence second-mentioned bearings, said hub and said first-mentioned bearings and said support.

2. A drum assembly comprising a drum, a drum flange connected to said drum, a shaft on which said drum and drum flange are mounted, a hub positioned axially of said shaft and spaced therefrom, a sprocket mounted in driving connection on said hub, a clutch between said sprocket and said drum flange, bearings positioned between the interior surface of said hub and the exterior of said shaft, a pillow block support for said shaft and bearing assembly, and a second bearing mounted on the exterior of said hub and between said hub and said pillow block, said bearings being positioned in series load-transfer relation with said shaft, said load-transfer relation including in sequence second-mentioned bearings, first-mentioned bearings, and said pillow block support.

3. A drum assembly, comprising a drum and drum ends, a shaft assembly on each end of said drum, said shaft assembly at each end of said drum comprising a drum flange connected to said drum, a shaft on which said drum and drum flange are mounted, a hub positioned axially of said shaft and spaced therefrom, a sprocket mounted in driving connection on said hub, a

6

clutch between said sprocket and said drum flange, bearings positioned between the interior surface of said hub and the exterior of said shaft, a pillow block support for said shaft and bearing assembly, a second bearing mounted on the exterior of said hub and between said hub and said pillow block, and means for driving said sprockets at different speeds.

4. A drum assembly comprising a drum, a shaft, said drum being mounted on said shaft, a sprocket axially mounted on said shaft, a fluid-operated clutch for connecting the drum and said shaft to said sprocket, an end support for said shaft, a bearing assembly between said shaft and said support, said bearing assembly comprising bearings between said sprocket mounting on said shaft and said support for transferring rotational loads from said sprocket to said support, other bearings positioned between said sprocket and said shaft, said bearings being positioned in series load-transfer relation with said shaft, said load-transfer series relation including in sequence said second-mentioned bearings and said first-mentioned bearings and said support, a fluid-pressure connection positioned on said support, axially of said shaft, a fluid passageway through said sprocket mounting on said shaft, and a fluid connection between said last-named passageway and said clutch.

5. A drum assembly comprising a drum, a drum flange connected to said drum, a shaft on which said drum and drum flange are mounted, a hub positioned axially of said shaft and spaced therefrom, a sprocket mounted in driving connection on said hub, a fluid-operated clutch between said sprocket and said drum flange, bearings positioned between the interior surface of said hub and the exterior of said shaft, a pillow block support for said shaft and bearings, a second bearing mounted on the exterior of said hub and between said hub and said pillow block, a closure at the end of said shaft and connected to said hub, enclosing said first-mentioned bearings, an air inlet mounted in said closure and axially of said shaft, a conduit in said hub and connected to said air inlet, and a fluid conduit connecting said hub conduit and said clutch.

6. A drum assembly comprising a drum, a drum flange connected to said drum, a shaft, said drum flange being mounted on said shaft, a sprocket disc and hub mounted for rotation on said shaft, a clutch air-pressure chamber mounted on said disc, a clutch plate mounted on said air-pressure chamber with its clutch face parallel to the axis of said shaft, a clutch ring mounted on said drum flange parallel to said clutch plate and in clutch-engaging relation with said clutch plate, an air inlet passageway positioned axially of said shaft, an air connection between said sprocket disc and said air-pressure chamber, and an air passageway connecting said inlet passageway and said air connection and mounted to rotate with said sprocket disc.

7. A drum assembly comprising a drum, a drum flange connected to said drum, a shaft, said drum flange being mounted on said shaft, a sprocket disc and hub mounted for rotation on said shaft, a clutch air-pressure chamber mounted on said disc, a clutch plate mounted on said air-pressure chamber with its clutch face parallel to the axis of said shaft, a clutch ring mounted on said drum flange parallel to said clutch plate and in clutch-engaging relation with said clutch plate, an air inlet passageway positioned axially of said shaft, an air connection between said

sprocket disc and said air-pressure chamber, an air passageway connecting said inlet passageway and said air connection and mounted to rotate with said sprocket disc, and a brake flange mounted on said drum flange and spaced from said clutch ring.

8. A drum assembly comprising a drum, a drum shaft, said drum being mounted on said drum shaft, a drum flange connected to said drum, a hub positioned axially of said shaft and spaced therefrom, a sprocket mounted in driving connection on said hub, a clutch between said sprocket and said drum flange, bearings positioned between the interior surface of said hub and the exterior of said shaft, a pillow block support for said shaft and bearing assembly, and a second bearing mounted on the exterior of said hub and between said hub and said pillow block.

9. A drum assembly comprising a drum, a shaft, said drum being mounted on said shaft, a sprocket axially mounted on said shaft, a clutch for connecting the drum and said shaft to said sprocket, an end support for said shaft, a bearing assembly between said shaft and said support,

5 said bearing assembly comprising bearings between said sprocket mounting on said shaft and said support for transferring rotational leads from said sprocket to said support, other bearings positioned between said sprocket and said shaft, said bearings being positioned in series load transfer relation with said shaft, said series load transfer relation including in sequence said second mentioned bearings, said first-mentioned 10 bearings, and said support.
